ELECTRICAL CONVERTER

Russell H. Varian, Stanford University, Calif., assignor to The Board of Trustees of The Leland Stanford Junior University, Stanford University, Calif., a corporation of California

Original application October 11, 1937, Serial No. 168,355, now Patent No. 2,242,275, dated May 20, 1941. Divided and this application March 23, 1940, Serial No. 325,634

17 Claims. (Cl. 250—27.5)

1

This invention relates generally to ultra high frequency radio apparatus and method, and the invention has reference more particularly to a novel converter and method for converting direct current into ultra high frequency alternating current. This application is a division of my copending application Serial No. 168,355, filed October 11, 1937, for Electrical converter, now Patent No. 2,242,275, issued May 20, 1941.

The principal object of the present invention is to provide an efficient generator or thermionic tube means for generating ultra high frequency alternating currents; said tube means having all ultra high frequency circuits substantially confined, thereby eliminating undesired radiation.

Another object of the present invention lies in the provision of a novel ultra high frequency oscillator employing a cavity resonator means together with means for projecting a stream of electrons therethrough for effecting bunching of the electrons of the stream and energy absorption from the bunched stream.

Still another object of the present invention is to provide a method of controlling the flow of electrons in an electron stream which comprises passing the stream through a region of standing electromagnetic waves provided in a hollow resonator to impart variable velocities to the electrons of the stream and then passing the electron stream into an energy absorbing region of electromagnetic waves, energy being conveyed from said energy absorbing region to the hollow resonator for maintaining the standing waves therein.

A further object of the present invention lies in the provision of a novel ultra high frequency oscillator having a cavity resonator for effecting velocity modulation of an electron stream and also having a second cavity resonator suitably spaced from the first so that the resulting density modulated stream, upon entering the second resonator, serves to set up and maintain a standing electromagnetic field therein, suitable feed-back means being provided between said second resonator and said first resonator to maintain oscillations in the latter.

Still another object is to provide an ultra high frequency oscillator utilizing a minimum starting current.

Yet another object of the present invention is to provide a method and apparatus for controlling the flow of electrons in an electron stream by passing the stream through a region of standing electromagnetic waves to impart variable velocities to the electrons of the stream, and then

2

passing the electron stream into an energy-absorbing region of electromagnetic waves, energy being conveyed from the energy-absorbing region to the first region for maintaining the standing waves therein.

A still further object of the present invention is to provide a method and apparatus for generating ultra high frequency waves by causing grouping of the electrons of an electron stream, absorbing energy from these groups of electrons by an electromagnetic field, which may be confined within a cavity resonator, and maintaining the groups of these electrons by energy conveyed from the energy-absorbing field to the grouping means.

Still another object of the present invention is to provide a method and apparatus for generating ultra high frequency waves by passing a stream of electrons thru a region of standing electromagnetic waves which may be confined within a hollow cavity resonator, and supplying energy from the stream leaving the region to maintain these standing waves.

My invention possesses numerous other objects and features of advantage, some of which, together with the foregoing, will be set forth in the following description of specific apparatus embodying and utilizing my novel method. It is therefore to be understood that my method is applicable to other apparatus, and that I do not limit myself, in any way, to the apparatus of the present application, as I may adopt various other apparatus embodiments, utilizing the method, within the scope of the appended claims.

Referring to the drawings:

Fig. 1 is a view, partly in longitudinal section and partly diagrammatic, illustrating an oscillator embodying my invention;

Fig. 2 is a fragmentary section of a slight modification of the structure shown in Fig. 1;

Fig. 3 is a view, partly in section and partly in perspective, showing a portion of the resonant circuit utilized in the tube shown in Fig. 1;

Fig. 4 is a plan view of the toroid space-resonant circuit and how it may be made resilient for tuning purposes;

Fig. 5 is a longitudinal sectional view of an oscillator tube embodying my invention, utilizing resonators having a relatively large power output and employing a large electron stream area.

Utilizing the principles of the present invention, I am able to build oscillating tubes having a high power output at ultra high frequencies which may be represented by wavelengths, for example, of ten centimeters or less, and I shall

describe a self-oscillator or converter wherein all of the resonant circuits are small enough to be self-contained within a single envelope. In this respect, I employ as a basic principle for the design of the oscillating circuits, a confined field resonator, in the form of a hollow metal internally space-resonant or tuned body.

To illustrate my invention, I have shown in the drawings a plurality of structures embodying my new method, in order that those skilled in the art may be able, from the disclosure herein, to build other apparatus following the same broad principles as claimed.

The word grid, as utilized herein, is deemed to refer to any electron-permeable electrode, irrespective of the number of apertures present, so placed as to influence electrons or to be influenced by them.

Referring directly to Fig. 1, which shows a thermionic tube or apparatus connected to control an electron stream, in accordance with my invention, an envelope 1 is provided at one end thereof with a reentrant stem 2 which supports a thermionic cathode 4. It is obvious that any of the known thermionic cathode structures directly or indirectly heated, may be utilized to form the source of electrons for the tube.

Under the influence of the field between the cathode 4 and a screen or accelerating electrode 20 produced by an accelerating battery 6, the negative terminal of which is connected to the electron-source cathode 4, the electrons emitted from the cathode 4 are caused to travel therefrom in the form of a stream along a substantially straight-line path. Along this path, the electrons travel through the screen 20, into and through a cavity resonator or space-resonant device 21, i. e., a dielectric resonator consisting of a dielectric-filled space, such as a vacuum or air space, adapted to contain standing electromagnetic waves resonant therein, and having a wave reflecting boundary surface, of the above described character. The electrons then travel through a space or region 24 and through a second cavity or dielectric resonator 25. The resonators 21 and 25 are electrically connected and illustrated with their outside surfaces at ground potential, the region 24 being shielded from the fields within said resonators.

Two parallel grids 9 and 10, forming part of the resonator 21, are disposed in the path of travel of the electron stream. Between these grids 9 and 10, the electrons are subjected to the action of an alternating electromagnetic field produced by oscillations within this resonator. After passing through the space-resonator 21 and through the space 24, the electrons enter the second space-resonator 25 through an anode grid 27, and travel thereafter through this space-resonator 25 to an anode or plate 12, which may be in the form of a solid wall. If desired the anode 12 may also be permeable as illustrated in Fig. 2. The electrons after passing through the permeable electrode 12 then may travel to a further anode 56. By reason of the nature of these resonators and their operation, the electromagnetic waves are multiply coherently reflected from the inner walls of the respective resonators. Because of their construction, shielding between the two resonant circuits of these resonators is practically perfect, and their respective alternating fields are thus completely electrically separated at the operating frequency.

The resonant alternating electromagnetic fields of these space-resonators, which comprise sus-

tained standing waves, are contained entirely within, so as to be bounded by, the conducting walls of the respective space-resonators. All conduction currents are on the inner surfaces of these walls. The portion of the field of the resonator 21 that coacts with the electron stream extends between the opposed inner surfaces of the grids 9 and 10. The portion of the field of the resonator 25 that coacts with the electron stream extends between the opposed inner surfaces of the grid 27 and the anode 12. Except for the openings through the grids 9, 10 and 27, these resonators constitute substantially closed and non-radiating containers, and while the openings in the grid structures permit the passage of the electrons, they do not permit the passage of an appreciable amount of electromagnetic radiation.

If desired, the anode 12 may also be permeable, as illustrated in Fig. 2. The electrons, after passing through the permeable electrode 12, may travel to a further anode 56.

The cathode structure 4 should be so designed, and the screen 20 so shaped, that the stream of electrons shall be focused into a collimated beam that does not spread excessively, notwithstanding that it is projected a considerable distance. The form of the screen 20 depends upon the physical configuration of the apparatus. Though it is connected through the frame of the apparatus to the positive terminal of the accelerating battery 6, it does not take part in the hereinafter-described cyclic operation of the system.

It is desirable, for the purpose of most efficiently practicing the invention, that the grids 9 and 10 be spaced to give an electron flight time therebetween substantially equal to or less than a half-cycle, or substantially an odd number of half-cycles, in accordance with the initial velocity of the entering electrons, and as determined by the frequency of the space-resonant device 21.

Each of the resonators 21 and 25 is shown as reentrant, as described in a copending application of William W. Hansen with David L. Webster, Serial No. 220,414, filed July 21, 1938, now Patent No. 2,227,372, issued December 31, 1940, the front reentrant poles being shown at 22 and 26, and the rear reentrant poles at 23 and 29. The resonators have substantially the exterior shape, roughly, of a toroid, as indicated in Figs. 3 and 4, except for the fact that the reentrant poles do not meet at, but are truncated before reaching, the respective centers of the resonators.

The grids 9, 10 and 27 may be in the form of multiple-apertured conducting members, as shown. The grids 9 and 10 are designed so as to offer as little obstruction to the passage of the electron stream as possible and are located at the inner extremities of the poles 22 and 23 of the resonator 21, and the grid 27 and the collector 12 are also located at the inner extremities of the poles 26 and 29 of the resonator 25. The grids 9, 10 and 27 serve to confine the resonator standing fields within the respective resonators. The electron stream, therefore, is projected through the pole 22 and the grid 9 before entering the resonator 21, through the grid 10 and the pole 23 after leaving it, and through the grid 27 and the pole 26 before entering the resonator 25.

Energy may be transferred to or from the electromagnetic field of a resonator of this character by means of inductive loops or capacitive elements in the field, as well as by means of a stream of electrons. In the oscillator of Fig. 1, the resonators are shown coupled together by a single coupling loop 30 that enters the respective

resonators through adjacent coupling slots 31 therein. The coupling loop 30 so interconnects the two resonators that any oscillation set up in one resonator shall cause an oscillation to be set up in the other resonator having a definite phase relation with the first. The space-resonant devices 21 and 25 are thus excited and unilaterally coupled together by the stream of electrons projected through their fields. That is, the beam of electrons will transmit a disturbance in resonator 21 to resonator 25, but with increased amplitude in this latter resonator. The beam will not transmit a disturbance in the reverse direction, however, and hence is unilateral in its action. The degree of insertion of this loop into the resonators controls the bilateral coupling. This coupling is termed bilateral because it can convey a disturbance between the resonators in either direction. The loop in this case conveys a part of the energy of oscillation in resonator 25 back to resonator 21 because the strength of the standing waves in member 25 is stronger than in member 21. The portion of the loop remaining outside may constitute or be coupled to a radiator or load circuit.

If the device is to act as a self-excited oscillator, the oscillatory field must be automatically built up by the action of the electron stream to a high level from a very minute transient value, such as that supplied by thermal agitation of electrons in the metal of the resonator 21, resulting in small departures from uniformity in the velocity or the density of the electron stream. It is essential, if oscillations are to be built up, that these small departures in density or velocity shall produce more powerful oscillations in the second resonator 25 than those existing in the first resonator 21, that produced them. In fact, they must be stronger by a sufficient margin so that more power can be fed back through loop 30 to resonator 21 than was initially present in resonator 21. If this condition is fulfilled, such transient field in resonator 21 will act to slightly speed up the electrons of certain portions of the electron stream and somewhat slow down other portions, while the speed of the remaining portions of the stream is unchanged. Electrons entering resonator 21 when the minute field therein opposes the stream will be decelerated while those that enter when the field aids the flow of the stream will be accelerated. In the space between resonators 21 and 25 the normal speed electrons tend to overtake the slower electrons while the faster electrons tend to overtake the normal speed electrons, so that slight electron grouping or bunching results. The electron groups on entering resonator 25 act to reinforce any transient field which may be present due to thermal agitation or other causes, and which is in such phase as to absorb energy from the incipient electron groups, whereas any transient field in a reverse phase will be damped out by delivering its energy to speed up the entering electron groups. The resonant circuit 25 will therefore automatically build up oscillations in such phase as to extract energy from any group of electrons appearing with the proper frequency between the grid 27 and the anode 12. If a portion of the energy in the resonant circuit 25 is transferred by feed-back to the resonant circuit 21, as by means of the coupling loop 30, in such phase as to enhance the minute oscillations between the grids 9 and 10 originally postulated, this enhancement of the oscillations will produce an increased degree of electron grouping

between the grid 27 and the anode 12 which, in turn, will increase the oscillations in the resonator 25. The initial faint oscillations in the resonator 21 will, therefore, become increased, thus still further increasing the grouping. This cyclic process may continue to produce stronger and stronger oscillations until a steady state of oscillation is achieved. After the oscillator has reached the stage of full oscillation, the energy of the grouped electrons is largely absorbed by the field in the space between the grid 27 and the anode 12.

Since the amount of energy delivered to the resonant element 25 by the bunching caused by a given field strength between the grids 9 and 10 is proportional to the current in the electron beam, the above conditions for the setting up of oscillations may be satisfied only if the current through the device exceeds a certain value. This minimum current that will result in oscillation, therefore, depends largely upon the losses involved in maintaining the oscillations between the grids 9 and 10 and between the grid 27 and the anode 12. For this reason the apparatus just described will operate on a very small starting current because of the exceptionally low losses inherent in cavity resonators 21 and 25.

In an amplifier, this coupling loop 30 may, of course, be omitted, unless feed-back is desired.

One actual preferred construction of the confined field resonators 21 and 25 is shown in Figs. 3 and 4. In Fig. 4, I have shown radial slots 35 in the resonator wall for the purpose of making the resonator slightly resilient so that the energy extracting resonator 25 may be tuned to the velocity modulating resonator 21, for example, by changing the spacing between the anode 12 and the grid 27. This is accomplished within the tube in one manner by sealing a metal bellows 32 to the end of the glass envelope 1, as shown in Fig. 1. A tuning rod 34 is connected to the end of this bellows 32 and may be moved to exert pressure against anode 12 by micrometer 33 bearing against stationary bearings 36. The slots 35 in resonator 25 may be very narrow, in which case they will not radiate appreciable amounts of energy. It is interesting to note that in the type of tube described above the only exterior connections necessary are the connections of battery 6 to cathode 4 and the resonators and all other connections are within the tube.

It can be shown both experimentally and mathematically that when the cathode ray beam is completely velocity grouped, the wave contains very sharp peaks of electron density. This is equivalent to saying that as the stream passes a given point the density variations with time possesses high peaks, so that the stream contains strong harmonic components. Because of this, it might be supposed that the harmonics of the velocity grouped stream would excite the harmonics of the hollow resonators, and thus produce a complex wave form. This is not the case, however, because the harmonics of the beam are integral multiples of the fundamental frequency, whereas the harmonics of the cavity resonators are in general not integral multiples of a fundamental frequency. Hence, if a particular harmonic of the hollow resonator corresponds to a particular harmonic of the grouped stream, it is unlikely that any other two harmonics will correspond, so that only a single harmonic frequency will be produced. Since

the resonance in the cavity resonator is very sharp, the device described is capable of generating a very pure sine wave.

In order for the electromagnetic waves in a hollow resonator to produce a maximum effect on the velocity of an electron during its transit therethrough, the electron flight time therethrough should be one half cycle or less, because if the field reverses before the electron gets through, some of the change in velocity will be canceled by the reversed field before the electron leaves the field. If the flight time in the field must for some reason be longer than one half cycle, it should be an odd number of half cycles, and then one half cycle of the field will be effective in changing the velocity of the electrons.

In causing an oscillator of the kind described to operate, it is necessary that the phase of the oscillations in the electron grouping resonator be such as to deliver electron groups in the right phase to enhance the oscillations in the energy absorbing resonator. It is generally easiest to meet this condition by adjusting the accelerating voltage of the electron beam, and thus to change the transit time of the electrons between the electron grouping resonator and the energy absorbing resonator.

The length of the flight time between the electron grouping and the energy absorbing means will depend upon the requirements of any particular installation. This flight time can be made very short if no regard is had for efficiency. The shorter the flight time is made, the stronger must be the excitation of the electron grouping circuit, because when the electrons have less time to catch up on each other, their velocity differences must be greater if they are to catch up within such short distances. This increased velocity difference introduces a difficulty in extracting the energy from the electron groups, for the fast electrons of a group will have considerably more energy than the slow electrons of the same group, and if the field extracts all the energy from the fast electrons, the slow electrons will be turned back, and will come out of the field on the subsequent half cycle with considerable energy. If the field extracts all the energy of the slow electrons, the fast ones will leave the energy absorbing means with considerable energy. This condition can be partially corrected for by rephasing the energy absorbing field slightly, but it cannot be completely cured if the flight time is made too short.

The advantage of the embodiment shown in Fig. 1 lies in the compactness of the apparatus, and the smallness of the current required to make it operate.

Figure 5 illustrates an embodiment of the invention which is preferred if large amounts of power are desired. It is necessarily of larger dimensions, but has very much larger power handling capacity.

In the device of Fig. 5, the resonators 21' and 25' correspond to the resonators 21 and 25 of Fig. 1. As in Fig. 1, resonator 21' is the electron grouping resonator, and resonator 25' is the energy absorbing resonator. In Fig. 1 the surfaces of the resonator are generated by rotation of the dumb-bell cross-section shown about the vertical axis of symmetry of the cross-section, thereby producing a spheroidal shape with pushed in poles which support the grids 9, 10 and 27.

The surfaces of the resonators of Fig. 5 on the other hand are generated by rotation of the off-

set or double dumb-bell cross-section shown about a vertical axis of symmetry of the resulting figure, producing a toroidal or annular figure with pushed in annular poles supporting annular grids 9, 10 and 27. The resonator of Fig. 5 may be considered to be generated by rotating the dumbbell cross-section of the resonator of Fig. 1 about an axis outside this cross-section but parallel to the axis of symmetry thereof. The resonant frequency of these resonators will be somewhat lower for a given cross-section of dumb-bell, i. e., on one side of the axis of symmetry, but not greatly so, whereas the area of grids 9, 10 and 27 is enormously increased. Since the power capacity is primarily governed by the area of these grids, this form will have a greatly increased power capacity.

In order to supply an annular beam of electrons to pass through grids 9, 10 and 27, cathode 4 is provided with an annular ring of emitting material 50. The electron beam is directed from emitter 50 through grids 9, 10 and 27, and excites the device in the same manner as already described in connection with Fig. 1.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim and desire to secure by Letters Patent is:

1. An alternating current generator comprising an annular cavity resonator comprising a toroidal structure consisting of two annular lobes connected by a narrow apertured annular isthmus, means for projecting an annular stream of electrons across said isthmus to set up a standing electromagnetic field within said cavity resonator, and coupling means extending into said cavity resonator.

2. Apparatus for generating high frequency currents comprising an electron emitter, hollow resonator means, means for projecting an electron stream from said emitter through said hollow resonator means to effect cyclic changes in the velocity of the electrons of said electron stream at the frequency of the hollow resonator means, a second hollow resonator means spaced from said first named resonator means in the direction of travel of said stream for absorbing energy of the frequency of said first resonator means from said electron stream and feed-back means coupling said second hollow resonator means to said first hollow resonator means.

3. Apparatus for generating high frequency currents comprising, means arranged to provide two mutually spaced regions and adapted to contain standing electromagnetic waves resonant therein, an electron emitter, means for drawing electrons therefrom through said first-named means for setting up standing electromagnetic waves therein and establishing alternating electric fields in said spaced regions for acting upon the electron stream, said first named means comprising feed-back means for conveying energy from the second of said regions to the first thereof for maintaining the oscillating field in the latter.

4. Apparatus for generating high frequency currents comprising, means having two mutually spaced substantially annular regions and adapted to contain oscillating electric fields.

means for emitting electrons, means for passing electrons from said emitting means in the form of an annular stream through said annular regions in succession for setting up the oscillating electric fields therein, said first named means including means for extracting energy from the field of the second of said regions and for using part of said energy to maintain the oscillating field in the first of said regions.

5. Apparatus for generating high frequency currents comprising electron emitter means for producing a stream of electrons of annular cross-section, annular hollow resonator means, means for projecting said electron stream from said emitter through said annular hollow resonator means to effect cyclic changes in velocity of the electrons of said annular stream at the frequency of the said resonator means, a second annular hollow resonator means spaced from said first resonator in the direction of travel of said stream for absorbing energy of the frequency of said first resonator means from said electron stream, and feed-back means coupling said second resonator means to said first annular hollow resonator means.

6. Apparatus for generating high frequency currents comprising, an electron emitter, hollow resonator means, means for drawing electrons in the form of a stream from said emitter through said hollow resonator means to effect periodic variation of the velocity of the electrons of said stream by the oscillating high frequency electromagnetic field transiently present in said resonator means, said periodic variation in velocity of the electrons of said stream resulting in recurrent grouping thereof after leaving said field, and means for supplying energy derived from said grouped electron stream to said hollow resonator means to maintain said hollow resonator means in a steady state of oscillation.

7. Apparatus for generating high frequency currents comprising, an electron emitter, annular hollow resonator means, means acting between said emitter and said hollow resonator means for projecting an annular electron stream from said emitter through said resonator means to effect periodic variation of the velocity of the electrons of said electron stream by the oscillating high frequency electromagnetic field transiently present in said resonator means, and means for supplying energy derived from said electron stream after varying the velocity thereof to maintain said hollow resonator means in a steady state of oscillation.

8. Apparatus for generating high frequency currents comprising conductive enclosing means having two mutually spaced regions and adapted to contain oscillating electric field portions resonant therewithin, means in said apparatus for producing an annular stream of electrons, means for passing electrons from said producing means through said regions in succession for setting up the oscillating electric field portions therein, said first-named means including feedback means for extracting energy from the field of said second region and for feeding back part of said energy to maintain the oscillating field in the first of said regions.

9. Apparatus for generating high frequency currents comprising a pair of spaced hollow resonators adapted to contain oscillating electric fields, means in said apparatus for producing an annular stream of electrons and for passing said stream through said resonators in succession for interacting with the oscillating elec-

tric fields therein, and feedback means coupling said second hollow resonator to said first hollow resonator.

10. Ultra high frequency apparatus comprising a pair of spaced hollow resonators, each resonator having a pair of electron permeable walls, means defining a drift space between said resonators, electrode means for projecting a beam of electrons and defining a path for said electrons through said resonators, said electron permeable walls and said drift space, and feed back means coupling said hollow resonators together.

11. Apparatus comprising a hollow resonator having a pair of aligned electron permeable portions, means in said apparatus for producing an electron stream, means defining a path for said stream through said resonator and said electron permeable portions, another resonator in said apparatus, and means coupling said resonators together.

12. In a sealed electronic tube having a glass base portion, an adjustable sealed mounting comprising a flexible metal member having a sealed connection to the base portion and an adjusting member extending through and sealed to the flexible member.

13. An adjustable mounting as set forth in claim 12, in which the metal member comprises a tubular metal element surrounding the adjusting member, mounted at one end on the glass base portion and connected at the other end to the adjusting member.

14. In a sealed electronic tube having a glass base portion, an adjustable sealed mounting comprising a flexible metal member having a sealed connection to the base portion, said member including a flexible tubular element, and an elongated adjusting member extending axially through said tubular element and sealed to said element adjacent the outer end thereof.

15. A hollow resonator having a pair of spaced gratings whereby an electron stream may be passed through the resonator for interaction of the electron stream with electromagnetic waves within the resonator, a source of an electron stream having a given average time rate of flow of electrons past said gratings, the spacing between the two gratings, and the ratio of open to closed area in the gratings being so proportioned as to provide at the said given average time rate of electron flow a predetermined degree of impedance match between the resonator as a source of waves and the grating as a means for controlling the storage of energy in the electron stream.

16. In combination, means for producing and maintaining a beam of moving electrons having a given average time rate of flow of electrons therein, and an electromagnetic resonator having a spaced pair of electron permeable electrodes arranged to provide passageway for the electron beam through and beyond said resonator, said electron permeable electrodes having a given spacing and being so designed as to the ratio of electron passing area to electron obstructing area as to give a predetermined degree of coupling for energy transfer between the resonator and the electron beam for electromagnetic variations at a predetermined frequency and for the given electrode spacing and average time rate of flow of electrons.

17. A velocity variation type oscillator comprising an enclosing vessel having a flexible wall portion, a cavity resonator fixedly mounted

within said vessel and having opposed walls provided with aligned apertures, one of said walls being flexible and opposite said flexible wall portion, an electron gun opposite one of said walls and in alignment with said apertures, an electrode opposite the other of said walls and in alignment with the aperture therein, and rigid means connecting said flexible wall portion to said flexible wall.
